UNITED STATES PATENT OFFICE.

FREDERICK W. VAN DUYN, OF NEW YORK, N. Y., ASSIGNOR TO R. E. DIETZ COMPANY, OF NEW YORK, N. Y.

LANTERN.

Application filed September 21, 1922. Serial No. 589,666.

To all whom it may concern:

Be it known that I, FREDERICK W. VAN DUYN, a citizen of the United States, residing at New York, in the county of New 5 York and State of New York, have invented a new and useful Improvement in Lanterns, of which the following is a specification.

This invention relates to lanterns of that kind in which the glass globe is detachably retained in place on the globe plate or support by a wire globe-protecting guard which bears with spring pressure against the globe. In some lanterns of this sort in which the globe plate is hinged to the lantern frame, 10 the globes have been provided with shoulders or projections for engagement by the guard wires for the purpose of holding the globe firmly on the globe plate and preventing it from shifting or falling when the globe 15 plate and globe are tipped back for exposing the burner, removing the globe or for other purposes. If the wire guards in such lanterns are proportioned so as to bear on the shoulders or projections with sufficient 20 force to hold the globes firmly and stationarily on the globe plates, the wire guard will not always spring into holding engagement with the shoulders or projections simply by shoving the globe endwise into 25 position on the globe plate or support, but it is frequently necessary to lift the guard wires by hand onto the holding projections or shoulders. It has also been proposed heretofore to make the globes with seg- 30 mental projections or portions on the opposite sides thereof intended to be engaged with and disengaged from the wire guard by turning the globe on the globe plate or support, but with such a construction more 35 or less care is required to see that the globe is not turned so far as to move the knobs or projections out of holding engagement with the wire guard, and if the globe should be accidentally turned on the globe plate or 40 support out of the intended position, the globe will not be held, and is apt to be displaced and broken. Furthermore, in globes of this sort heretofore made, the projections have been of such form that they do not al- 45 ways insure the proper engagement of the guard wires with the projections by the turning of the globe on the globe plate, and it is frequently necessary to lift the guard wire by hand into engagement with the pro- 50 jections.

The object of this invention is to overcome the objections to the constructions heretofore known, and to provide a globe having a holding shoulder and guard-engaging portions or projections, so constructed as to insure that the guard can be properly engaged with the holding shoulder of the globe simply by moving or turning the globe, and will hold the globe firmly, and so as to prevent the releasing of the globe in the event 60 that the same should be accidentally turned on the plate or support to a position in which the guard-engaging projections or portions of the globe are not in alinement with the holding portions of the guard. 65

In the accompanying drawings:—

Fig. 1 is a front elevation of a tubular lantern provided with globe holding means embodying the invention.

Fig. 2 is a side elevation thereof showing 75 the globe and globe plate tipped back.

Fig. 3 is a fragmentary side elevation of the globe and guard showing the camming position of the cam projection when lifting the guard wire. 80

Fig. 4 is a similar view showing the holding position of the parts.

Fig. 5 is a horizontal section of the globe.

Figs. 6 and 7 are fragmentary sections of the globe on lines 6—6, and 7—7 respectively, Fig. 5. 85

A represents the oil pot, B the tubes, C the top, D the spring pressed chimney or globe holder, E the globe lifting shaft, F the hinged globe-supporting plate, and G the globe guard of a tubular lantern of known type. The globe supporting plate, as usual, is connected to the lifting shaft by a suitable hinge *f* which permits the globe plate to swing rearwardly from its normal position 90 over the burner. The globe guard may be of any usual or suitable construction, the guard shown being of the well known cross wire type, in which two oblique wire bows 10 cross each other at the front and rear 95 sides of the lantern and have bent top portions adapted to bear against the holding shoulder or projections on the globe. 100

The globe is formed with a circumferential, external shoulder or offset 11, which 105 preferably extends completely around the globe at a point between the ends of the globe, such that the upper portions of the guard wires are adapted to bear on the shoulder at opposite sides of the globe for 110

holding the globe in place on the globe plate F. At its opposite sides the globe is also provided with two guard-engaging projections or portions 12, which extend upwardly 5 on the sides of the globe from points below the circumferential shoulder 11, and terminate at their tops at or substantially at the shoulder 11. These projections are preferably of wedge shape, or increase in thickness 10 from their lower to their upper ends, and have downwardly diverging edge portions 13 which are adapted to act as cams for engaging the guard wires and moving them onto the tops of the projections or onto the 15 circumferential shoulder 11, by turning the globe on the globe supporting plate F. These projections 12 are disposed at opposite sides of the globe and extend only a comparatively short way around the globe 20 so that the globe can be placed within the guard on the globe plate F, with the projections 12 located between the converging upper portions of the guard wires.

By placing the globe on the globe plate 25 in this position, and then turning the globe partway around in either direction on the globe plate, the diverging edges 13 of the projections will engage the opposite portions of the guard wires and act as cams to 30 lift the guard wires up onto the tops of the projections or onto the circumferential shoulder 12, which is preferably coincident with the tops of the projections. After the 35 guard wires have been thus engaged with the circumferential shoulder 11, it is not necessary for the globe to remain in a position in which the projections 12 are alined with the top portions of the guard, but the globe can be turned to any position on the globe 40 plate F, and the guard wires will remain in engagement with the circumferential shoulder and securely retain the globe in position on the globe plate irrespective of the 45 position to which the globe may be turned. The projections 12, being, as explained, of wedge shape, the globe can be pushed straight down into the guard and if the 50 position of the globe is such that the projections engage the top portions of the guard wires the wires will ride up on the projections, and in many instances, will snap over the tops of the projections. But if the guard fails to be moved into holding engagement with the projections in this way,

then, by turning the globe, as explained, the 55 projections act as cams to move the guard wires into holding engagement with the circumferential shoulder 11, and thereby insure the proper fastening of the globe, notwithstanding that the upper portions of the 60 guard wires may, and preferably do, normally stand below the tops of the projections to insure a very firm pressure of the globe downwardly upon the globe plate. After the engagement of the guard wires 65 with the tops of the projections or the shoulder 11, the globe cannot be accidentally moved out of holding engagement with the guard by the accidental turning of the globe to a position in which the projections 12 are 70 moved from beneath the holding upper portions of the guard wires.

I claim as my invention:

1. In combination in a lantern, a globe supporting plate, spaced holding members 75 thereon arranged to bear against the globe, and a globe having a circumferential shoulder arranged to be engaged by said holding members for holding the globe on the supporting plate, and said globe also 80 having cam-like portions which diverge from said shoulder and are adapted by turning the globe to engage said holding members to move the same into holding engagement with said shoulder. 85

2. The combination of a globe supporting plate, a globe guard thereon having holding portions which partially encircle and bear against the globe, and a globe having a continuous shoulder which completely encircles 90 the globe and is arranged to be engaged by said holding portions of the guard for holding the globe on the globe plate, and said globe also having cam-like portions cooperating with said shoulder and adapted by 95 turning the globe to engage said holding portions of the guard and move the same into holding engagement with said shoulder.

3. A lantern globe having a circumferential shoulder adapted to be engaged by the globe guard of a lantern for holding the globe on the globe supporting plate, and also having cam-like portions which extend from said shoulder and are adapted to engage the guard and move the same into 100 holding engagement with said circumferential shoulder. 105

FREDERICK W. VAN DUYN.
